KNITTING MACHINE

Samuel Saftlas, Newark, N. J.

Application July 23, 1946, Serial No. 685,705

4 Claims. (Cl. 66—147)

1

This invention relates to a method of, and means for, printing on knit fabrics. More particularly it relates to printing mechanism adapted to print such fabrics as the latter comes from the knitting instrumentalities of the knitting machines.

I am aware that various attempts to print on such fabrics have been made, and while the desirability of providing designs on such fabrics in this manner have long been recognized, no satisfactory method or means for accomplishing this has been devised.

Providing printed designs on knit fabrics presents many difficulties inherent in the nature of knit fabrics. Knit fabrics have a characteristic appearance due to their stitch formations and designs applied to such material by ordinary printing methods present a displeasing effect due in large measure to the lack of conformity of the printed designs to the particular stitch formation of the fabric.

It is the principal object of my invention to overcome these difficulties and provide a method of and means for producing a printed knit fabric in which the printed areas conform sufficiently close to the stitch formations so that the resulting design appears as a unitary part of the fabric, uniformly applied and giving an appearance in keeping with the knit character of the fabric.

Another object is to provide a novel and improved printed knit fabric.

Other and further objects residing in the details of the method and apparatus will be made apparent in the following specification and claims.

One feature of the invention is the application of the color to the fabric while the fabric is under a substantially uniform surface tension, a second and essential feature is the provision of means actuated by the movement of the fabric which conforms the movement of the fabric to the movement of the printing roll, all as set forth in detail hereafter.

In the accompanying drawings which diagrammatically disclose the application of my invention to circular knitting machines,

Fig. 1 is a fragmentary plan view showing the invention embodied in a machine of the stationary cylinder type;

Fig. 2 is a sectional view substantially on line 2—2 of Fig. 1;

Fig. 3 is a fragmentary elevational view looking from the right of Fig. 2;

Fig. 4 is a diagrammatic view illustrating the action of the coordinating roll;

2

Fig. 5 is a vertical sectional view showing the invention embodied in a knitting machine of the rotary cylinder type; and

Fig. 6 is a sectional view substantially on line 6—6 of Fig. 5.

In the drawings only such parts of the knitting machines are shown as are necessary to an understanding of the invention and the relative size and proportions of the parts have been exaggerated or diminished as convenience and clearness of disclosure required. For example, the relative diameter of the knitting cylinders are substantially greater in actual practice than is indicated in the drawings.

Referring to Figs. 1, 2 and 3, a stationary knitting cylinder, indicated at 10, is supported by a table or frame member 11 to which the cylinder is secured as by screws 12. The tubular body of knitted fabric, passing downwardly through the cylinder, is indicated at 13. The fabric goes through fabric advancing rolls 9 (Fig. 1), to a take up roll, not shown. The fabric as it leaves the knitting instrumentalities is under tension and is in a stretched condition with the stitches partially opened. At a point sufficiently close to the top of the cylinder so that the fabric is not completely relaxed and the stitches are not completely closed I mount one or more printing units 14, each comprising a printing roll 15 and an associated coordinating disc 16. As shown these printing units act on the outer surface of the fabric but they could be supported to engage the inner surface, or both surfaces could be printed, if desired. The roll 15 and disc 16 are mounted on a common shaft 17 so that the disc will drive the roll as later described. The ends of shaft 17 are journaled as at 18 in the side extensions 19 of a small color reservoir 20, which is supported on a bracket 21 which extends through an opening 22 in cylinder 10 and is secured as by screws 23 to table 11. Color, or other printing material, is supplied to reservoir 20 through a pipe 24 passing through opening 22 to any suitable form of supply tank 25 from which color is supplied to the individual reservoirs 20. As shown, the supply tank 25 is annular in form and is supported on brackets 26 mounted on table 11 at any suitable distance from the knitting cylinder. When different colors are to be supplied to different printing units the tank 25 may be partitioned or separate supply tanks used. The reservoirs 20 are provided with covers 27 formed with an opening 28 through which the rolls 15 contact the color, the covers 27 are formed with recesses 29 in which

the discs 16 rotate so that no color is taken up by the discs.

As perhaps best shown in Fig. 4, the periphery of each coordinating disc 16 is formed with a plurality of spaced teeth 30, the spacing being such that the teeth 30 enter and follow a linear series of stitch loops 31. Since the fabric engages the disc over a small arc, several teeth are in engagement with a succession of loops at all times and the disc follows along a vertical wale of the fabric. The printing roll 15, which is mounted closely adjacent the disc 16, will also print along a wale since the disc 16 maintains a local control of the fabric at the point where the color is applied. Where a number of printing units are closely spaced around the cylinder the multiplicity of control points increases the accuracy of the color applications as a whole.

A single coordinating disc 16 may control two adjacent printing rolls 15 as indicated at the units A in Fig. 1, or where the type of stitch or character of thread render control difficult two coordinating discs may be used one at each side of a single printing roll as indicated at unit B in Fig. 1. The conditions permitting or making desirable one or the other of the several disc arrangements may be local as in rib knit fabrics or may prevail over the fabric as a whole. To increase the overall accuracy of the printing operation, independent discs 16 may be positioned as at C between the printing units.

As best shown in Fig. 3 the diameter of the printing surface of roll 15 is less than the diameter of the disc 16 at the point of the teeth 30 but it is greater than the diameter at the bottom of the spaces between the teeth, so that the printing roll exerts a pressure on the fabric adequate to transfer the color without the disc losing control of the fabric. The engagement of the teeth 30 in the stitches of the downwardly moving fabric rotates the disc to drive the printing roll without substantial slippage between the printing roll and fabric, and the color is applied to the fabric in a predetermined relation to the linear series of stitches engaged by the teeth of the disc.

The faces of the printing rolls may be of a width to color one or more wales and the roll surface may be continuous to apply a continuous strip of color or the surface may be broken to give a dot, dash or other desired effect.

In Figs. 5 and 6 I have shown my invention applied to a rotary cylinder type of machine. In this type of machine the knitting cylinder, indicated at 35, is constantly rotated as by a pinion 36 which meshes with a ring gear 37 formed on an annular member 38 to which the cylinder is secured as by screws 39. The tubular fabric 40 descending through the cylinder rotates with the latter and as shown is wound up on a take up roll 41 mounted on a rotary table 42 driven by a pinion 43 meshing with a ring gear 44 secured to the under side of the table. A gear 45 on the shaft 46 of pinion 36, and a gear 47 on the shaft 48 of pinion 43 both mesh with a driving gear 49 so that the cylinder 35 and windup roll 41 rotate in synchronism. The windup roll 41 is supported in bearing members 50 which also support rolls 51 engaging opposite sides of the fabric tube. The windup roll 41 may be driven by an electric motor 52 through gearing generally indicated at 53, the lead for the motor passing through the axis of the table as indicated at 54. Any other suitable type of windup may be used.

Within the tubular fabric is placed a frame structure 55 comprising vertically spaced hori-

zontal spreading rings 56 supported by arms 57 from a plate member 58. The lower edge of plate member 58 is rounded as at 59 and rests on the fabric where the latter enters between rolls 51. The fabric tube is thus drawn over the frame structure 55 which rotates with the fabric. Ring members 56 are of a diameter to stretch the fabric sufficiently to open the stitches of the fabric, to maintain the fabric as it passes over the frame between rings 56 in substantially the tensioned and opened condition previously described with regard to the stationary cylinder machine at the point where previously described discs 16 operate.

One or more printing units 60, only one of which is shown in Fig. 5 for the sake of clearness, are mounted on brackets 61 secured to a stationary part 62 of the machine frame by screws 63.

The printing unit 60 is substantially the same as unit 14 and comprises a printing roll 64 and coordinating disc 65 which may be identical with those previously described except that they are set to rotate in a plane tilted slightly from the horizontal so as to follow a linear series of stitches comprising a spiral knitting course instead of a vertical wale. The unit 60 includes a small color reservoir 66 supplied through a pipe 67 from a supply tank not shown. The roll 64 and disc 65 are secured on a shaft 68 journaled at 69 in the side of the reservoir. Color is applied to roll 64 in any suitable manner as by a felt transfer disc 70 or the like secured to a shaft 71, driven by the printing member or any suitable means, not shown, from some rotating element of the machine.

Since the movement of the tube of fabric relative to frame 55 is directly downward, one or more free coordinating discs, such as that indicated at 72, may be secured to frame 55 to engage the inside of the fabric and follow a vertical fabric wale and prevent any tendency of the fabric to creep or shift around the frame 55. Printing rolls could of course be associated with the discs 72 to print on the interior of the fabric if desired.

The coordinating disc 65 follows a spiral knitting course laid down by one of the several yarns or threads being fed to the knitting machine so that the turns of the spiral being followed are spaced an appreciable distance apart. For example, assuming a 32 feed machine, the turns of the spiral knitting course followed by a given printing unit will be spaced 32 courses apart. One or more of these 32 intermediate courses may, of course, be printed upon by the printing rolls of other printing units as shown in Fig. 6.

As previously described the printing rolls may be made wide enough to print on more than one knitting course and the printing surface of the roll may be broken to give any desired design pattern. Furthermore, by proper proportioning of the diameter of the printing roll, and its coordinating roll, to the diameter of the fabric tube at the point of printing, further variations in design may be secured. For example, assuming a dot design is being applied by the printing roll, the diameter of the printing roll may be made such that the dots applied to successive turns of the spiral course will fall in a vertical line beneath those of the preceding turn, or between them. By this means, using various forms of printing surfaces and diameter proportions, my invention makes it possible to build up many varied and relatively complicated designs.

It will be understood that my invention is applicable to any desired printing or coloring

method. For example instead of the direct application of color by the printing members, the latter may apply a resist or discharge chemical which after the fabric has been subjected to a dyeing operation may be discharged or washed away to form a predetermined design area on which the discharge chemical had been applied.

It will also be understood that the printing surfaces of the printing rolls may be smooth or may be shaped to carry the color or other design forming material into the interstices of the fabric where the nature of the yarn or the viscosity of the color or other applied material requires.

By my invention a positive control of the rotary movement of the printing rolls is obtained regardless of variations in the cloth tension in the machine, loosening or tightening of the stitches as the machine changes speed, or spasmodic changes in the pull of the take up. Regardless of variations which ordinarily take place in the conditions of operation of the knitting machine the printing roll is held to a predetermined position relative to the stitches of the fabric, and cannot get out of time, slip or wander. With prior art printing devices the amount of defective cloth from these causes has been prohibitive, especially where discharge printing was employed and the defects appear only after the washing, in subsequent operations. By my invention defects from these causes are substantially done away with, or so minimized that a commercially practical operation is attained.

The overall design printed on the fabric is made up of a plurality of independently applied linear patterns each having a predetermined relation to a linear series of stitches. The linear pattern of each printing member is accurately applied with relation to the linear series of stitches engaged by the toothed disc associated with the printing member, and since each printing member and its associated disc operates independently of the others slight deviations in the several units are not accumulative nor are they transmitted from one unit to the other. Inasmuch as the circular knit fabric is printed on while in tubular form complete continuity of design is obtained around the entire surface of the tube.

What I claim is:

1. In a circular knitting machine having wind up means to draw the tube of fabric under tension from the knitting instrumentalities, a pair of spaced spreading rings positioned within the tube of fabric between the knitting instrumentalities and the wind up and over which the fabric travels in tensioned cylindrical form, a rotary printing member mounted in printing engagement with the surface of the fabric between said rings, means to supply printing material to said printing member, a disc, a shaft common to said printing member and disc, and teeth formed on the periphery of said disc and engageable in a linear series of stitches of the fabric to rotate the printing member and maintain the application of printing material to the fabric by the printing member in a predetermined relation to the linear series of stitches engaged by said teeth.

2. In a circular knitting machine having a rotatable knitting cylinder and a rotatable wind up means to draw the tube of fabric under tension from the knitting cylinder, a frame including spaced spreading rings, positioned within the tube of fabric between the knitting cylinder and the wind up means and rotatable therewith, a revolving printing member mounted for printing en-

gagement with the fabric as the latter passes over the space between the rings, means to supply printing material to said printing member, a revolving member having teeth engageable in a linear series of stitches of the fabric, and a driving connection from the revolving member to the printing member to drive the latter and maintain the application of printing material to the fabric by the printing member in a predetermined relation to the linear series of stitches engaged by the teeth of the revolving member.

3. In a circular knitting machine, a rotatable shaft positioned to one side of the path of the tube of fabric formed by the machine, a disc fixed on said shaft to rotate in a plane radial with respect to the axis of the tube, the periphery of said disc being provided with a plurality of teeth successively engageable in successive openings of a linear series of stitches, a printing member fixed to said shaft and spaced from said disc to engage a neighboring linear series of stitches, means to supply printing material to said member, and means to apply sufficient tension to the tube of fabric to maintain the teeth of said disc in engagement with the openings of a single linear series of stitches and impart constant rotation to said shaft and printing member and confine the application of printing material to the fabric by said member to said neighboring linear series of stitches.

4. In a circular knitting machine, a shaft rotatably mounted to one side of the path of the tube of fabric formed by the machine, a disc fixed on said shaft to rotate in a plane radial with respect to the axis of the tube, the periphery of said disc being provided with a plurality of contiguous generally triangular teeth successively engageable in successive openings of a linear series of stitches, a printing member fixed to said shaft and axially spaced from said disc to engage a neighboring linear series of stitches, the radius of the printing surface of said member being intermediate between the radius of the points and the radius of the bases of the teeth of the disc, means to supply printing material to the printing surface of said member, and means to apply sufficient tension to the tube of fabric to assure entrance of successive teeth of the disc into successive openings of a single linear series of stitches up to a depth that will maintain the printing surface of the adjacent printing member in printing contact with said neighboring linear series of stitches and impart uniform rotation to said shaft.
